DETECTION ARRANGEMENT AND NEGATIVE IMPEDANCE FOR SAME

Frederick E. Terman, Stanford University, Calif., assignor to International Standard Electric Corporation, New York, N. Y., a corporation of Delaware

Application June 30, 1939, Serial No. 282,055

5 Claims. (Cl. 178—44)

The present invention relates to improved circuit arrangements for performing a detection, and particularly to such arrangements wherein a rectifier is used to detect the modulated carrier wave so as to produce therefrom a wave corresponding to the envelope of the modulated wave.

The invention also relates to a novel type of circuit unit having the current/voltage characteristics of a negative admittance, which is employed in the improved circuit arrangement above mentioned but which is also suitable for other uses.

It is an object of the present invention to improve the action of detectors, especially detectors of the rectifier type. Especially it is an object to reduce the occurrence of distortion in such a detector and to enable such detector to be employed for detecting modulated waves having a depth of modulation approaching 100% without giving rise to distortion or over-modulation. It is a particular object of the present invention to raise the alternating current impedance presented to a diode detector to a value substantially equal to the value of the direct current impedance presented to such detector, in order to cause the diode to faithfully detect modulated signals without alteration of the effective modulation depth, and in order to reduce distortions and permit the detector to be used with modulated signals having a depth of modulation approaching 100%.

In accordance with one feature of the present invention the raising of the alternating current impedance presented to a detector of the rectifier type by the load circuit of such detector is effected by connecting a unit having the characteristics of a negative admittance across a portion of such load circuit. It is a further object of the present invention to provide an improved type of unit which shall have the characteristics of a negative admittance and which shall be suitable for use not only for raising the effective alternating current impedance of the load circuit of a detector in accordance with the principal object of the invention, but also generally for all other uses for which negative admittance units are desired.

In modern radio receivers and other communication devices a common form of detector arrangement for deriving the envelope wave from a modulated wave is the so-called diode detector employing a simple half wave or full wave rectifier of the space discharge type for performing detection. Such diode detectors are gen- 55

erally used in a circuit whose impedance with respect to direct currents is somewhat higher than its impedance with respect to audio frequency currents. As a result of such disparity 5 between the direct current and alternating current impedances which form the effective load for the diode detector, it is usually found that the direct current output from the diode does not bear as great a ratio to the audio frequency current output from the diode as the mean carrier amplitude of the high frequency waves fed to the diode bears to the audio frequency amplitude variations of such high frequency waves fed to the diode.

In other words, because of the smaller impedance offered to alternating current in the output circuit of the usual diode detection arrangement, the changes of carrier amplitude which correspond to audio frequency signal 10 waves are more effectively detected than the unchanging or mean value of the carrier waves which correspond to the direct current output from the detector. When, therefore, a wave whose depth of modulation is equal to or close 15 to 100% is applied to such a detector, it results that the corresponding output wave of the detector tends to be a pulsating current whose direct current component is smaller than its alternating component as a result of the greater 20 effective impedance of the detector circuit for direct current than for alternating current. This means that the output current tends to actually reverse in polarity. Because of the unidirectional characteristic of the diode detector 25 such a reversal cannot take place, and therefore a corresponding flattening of the troughs of the audio frequency output wave necessarily takes place.

One of the principal objects of the present 30 invention is to eliminate such distortion. Briefly this is accomplished by making use of a circuit element having the characteristics of a negative admittance for raising the effective alternating current impedance of the load circuit of a diode detector so that this alternating current impedance shall become substantially equal to the corresponding direct current impedance of the load circuit.

The exact nature of the invention may best be 35 understood by reference to the attached drawing, in which—

Fig. 1 represents a diode detector connected to a circuit arrangement which serves both as a two-stage audio amplifier to amplify the output 40 of the detector, and also simultaneously serves

to present a negative admittance at points $x-x$ of the diode output circuit; and

Fig. 2 represents an alternative arrangement wherein the negative admittance effect across terminals $x'-x'$ is produced by alternative means.

Referring more particularly to Fig. 1, the diode detector 1 and its tuned input circuit 2 are connected in series with an output or load circuit which primarily includes the resistor 3 and the resistor 4 which is capacitively coupled through condenser 5. The carrier frequency by-pass condenser 6 is also provided across the output circuit in order to by-pass the carrier frequency. The carrier frequency input to tuned circuit 2 is supplied inductively in the usual manner. Such a circuit arrangement is in itself typical of the conventional circuits heretofore used for detection by means of a diode rectifier. As conventionally used such a detector circuit would be connected at the terminals $x-x$ to the input of an audio frequency amplifier which in turn would be connected to a loudspeaker or to a further output stage of audio amplification. The audio frequency amplifier which would conventionally be connected at terminals $x-x$ would offer to the output circuit of the diode an essentially capacitative impedance so that so far as the impedances presented to the diode are concerned this amplifier might be considered as equivalent to a further condenser shunted across the resistor 4.

From inspection of the output circuit 3, 4, 5, 6, it will readily be seen that the direct current impedance of this output circuit is necessarily higher than the corresponding alternating current impedance thereof. If it be assumed that resistors 3 and 4 are both of the same order of magnitude and if the capacity provided by the amplifier across terminals $x-x$ be neglected, it would follow that the alternating current impedance would be approximately one-half of the direct current impedance. If any signal more than 50% modulated were applied to input circuit 2, over-modulation and consequent distortion would result in the output of the diode.

The undesirable ratio of direct to alternating current impedance could, it is true, be reduced by making resistance 4 very large in comparison with resistance 3, but in practice it is usually not possible to make resistance 4 higher than a few megohms, and since resistance 3 is generally at least of the order of a fraction of a megohm, it is ordinarily not practicable to obtain substantial equality of the alternating current and direct current impedances by simply raising resistance 4. It should furthermore be noted that even if resistance 4 were made infinite the alternating current impedance would still be somewhat smaller than the direct current impedance because of the capacitive admittance provided by the wiring and by the input circuit of the following audio amplifier.

In accordance with the present invention the audio amplifier not only does not present a capacitive admittance for increasing the disparity between direct current and alternating current impedances, but actually this amplifier is so connected as to present at the terminals $x-x$ a negative admittance, thus serving to neutralize the positive admittance of resistor 4.

The connections of the negative admittance unit shown in Fig. 1 to the right of terminals $x-x$ differ from those of a conventional amplifier principally in the connection of the three

impedances N, P, Q, so as to form with the impedance of the detector circuit a sort of bridge circuit, and in the fact that the cathode lead of the second amplifier tube t_2 is returned not to ground but to a point intermediate to the resistors N and Q.

The three impedances N, P, Q, which are shown as simple resistors in Fig. 1, are connected so as to form with the external impedance M connected across the terminals $x-x$, a sort of bridge circuit as shown. The symbol M is used for convenience to represent the total effective impedance of the diode detector circuit as seen from terminals $x-x$. If the condenser 5 is very large the impedance M will be very nearly equal to the resistance of resistors 4 and 3 in parallel.

The control grid of tube t_1 is connected as shown, to one corner of the bridge M, N, P, Q, while the cathode is returned to the diagonally opposite corner of the bridge which is grounded. The cathode of this tube t_1 is given a suitable positive direct current bias with respect to ground by means of resistor 7. Since the control grid of tube t_1 is essentially at ground potential with respect to direct current by connection through resistors P and 4 or Q and N, this positive cathode bias provided by resistor 7 has the effect of making the grid more negative than the cathode as desired. With respect to all desired audio frequencies, however, the cathode of tube t_1 is substantially short circuited to ground through condenser 8 so that this cathode may be regarded as directly grounded with respect to signal frequencies.

The suppressor grid of tube t_1 is directly connected to this cathode and its screen grid is effectively short circuited to the cathode with respect to signal frequencies through condenser 9. Over high resistance 10 the desired direct current bias for the screen grid of tube t_1 is supplied by battery 11. The plate of tube t_1 is fed with the necessary positive direct current from battery 11 over feed resistor 12 and coupled over condenser 13 and grid resistor 14 to the control grid of the next tube t_2 .

The cathode of the second tube t_2 is returned to the lower corner of bridge M, N, P, Q, as shown. The suppressor grid of this tube t_2 is directly connected to the cathode and the screen grid is effectively short circuited to this cathode so far as the signal frequencies are concerned over condenser 15, being fed with the required positive direct current bias over resistor 16 from battery 11. The plate of tube t_2 is fed over impedance 17 (which is shown as an inductive high impedance) from battery 11. Output coupling condenser 18 couples the plate of tube t_2 to one of the output terminals o-o and also to the other corner of the bridge M, N, P, Q. The cathode of tube t_2 is correspondingly connected to the other of the output terminals o-o and to the lower corner of the bridge M, N, P, Q.

The operation of the negative impedance element shown to the right of terminals $x-x$ in Fig. 1, can best be explained by assuming that an electromotive force E_s is produced by the action of the diode detector. Not all of this voltage will be effective across the input of tube t_1 , but the drop in N and the drop in Q will both be effective to form a signal applied between ground and the control grid of tube t_1 . This voltage between the grid of tube t_1 and ground will give rise to an amplified voltage across the output of the amplifier, which output voltage will serve to energize the loudspeaker or other

load (not shown) which is connected across o—o. This output voltage is not only effective across the loudspeaker or other load, but is also fed back to the upper and lower corners of the bridge M, N, P, Q. Assuming for convenience of discussion that

$$M = \frac{NP}{Q}$$

so that $M:P=N:Q$, then no voltage drop between the grid of tube t_1 and ground will be produced by such fed back voltage and therefore substantially no degeneration or regeneration will occur. A very considerable current, however, will flow through the external impedance M (i. e. through the external circuit connected to the terminals x—x which in this case is the diode detector circuit). Such current through M will cause a voltage drop in M so that the total voltage across x—x will be the original E. M. F. E_s plus the added drop due to the current in M.

It should be noted that the sense or polarity of this current through x—x is so related to the total voltage existing across x—x, as to correspond to a negative impedance or more properly a negative admittance on the right of terminals x—x. Furthermore, the approximate magnitude of the negative admittance can be estimated as follows: It can be seen by inspection that if the impedance of M is substantially greater than NP/Q so that the bridge M, N, P, Q, is considerably unbalanced, then clearly oscillations will occur if the gain of the amplifier is reasonably great. Since the occurrence of oscillations indicates that the admittance of M is smaller in absolute magnitude than the negative admittance presented by the unit to the right of x—x, this means that for reasonably large values of voltage amplification the value of the negative admittance is only slightly smaller in absolute magnitude than the value of positive admittance which M must have to balance the bridge M, N, P, Q. In other words, the admittance presented at x—x by the back-connected-amplifier arrangement will be approximately $-Q/NP$ if a is large. The quantity a is the voltage amplification, i. e. the ratio of the voltage across o—o to the voltage across grid-cathode of tube t_1 under actual operating conditions.

For more accurate computation of the negative admittance offered by the unit the impedance M is assumed to be zero, or NP/Q , or any other convenient value, and then the ratio of the current through x—x to the voltage across x—x is computed for an assumed voltage of E_s . If the impedance of t_1 be considered infinite and the impedances of 8, 9, 13, 15, 18, be considered zero the negative admittance at x—x is

$$\frac{Q - \left(\frac{P+Q}{a}\right)}{NP + \left(\frac{P+Q}{a}\right)N}$$

It will be noted that in actual operation M need not have the value zero nor the value NP/Q as assumed above, since the value of the negative admittance presented at x—x is independent of the external circuit at least if the impedance M of this external circuit is not so great as to cause instability and oscillation. For very many purposes, however, it is desired that the negative admittance of the unit at x—x should be nearly equal and opposite to the positive admittance of the connected circuit. In such cases M will be roughly equal to NP/Q .

In the above discussion certain second order effects have been neglected for the sake of simplicity. In the first place, it should be noted that even if the bridge M, N, P, Q, be perfectly balanced so that no potential difference between the grid of tube t_1 and ground arises by virtue of the feedback voltage from the plate and cathode of tube t_2 to the upper and lower corners of the bridge, still under these conditions a slight degeneration will be present because of the fact that both the grid and filament of tube t_2 will be made more positive, thus decreasing the effective plate voltage of tube t_1 . Also it should be noted that a slight degeneration or negative feedback from the output of tube t_2 to the input of this very tube exists by virtue of the fact that the plate circuit of tube t_2 includes resistor N while at the same time the input to this tube t_2 is applied from tube t_1 not between the grid and cathode, but between the grid of tube t_2 and ground. The drop in resistor N caused by the output current of tube t_2 is therefore degeneratively applied to the input of this very tube. It should be noted, however, that the degeneration occurring between the output and input of tube t_2 itself may be considered as equivalent merely to a reduction in the effective amplification of this tube and thus is taken into account in the measured value of a . Similarly the slight degeneration or negative feedback existing around the whole amplifier from the output of tube t_2 to the input of tube t_1 by virtue of the reduction of effective plate voltage which occurs when both the filament and the grid become more positive is also automatically included in the calculations if a is measured under operating conditions.

For the purpose of eliminating distortion in the diode detector circuit, the best adjustment of the negative admittance presented by the unit is one which raises the alternating current impedance of the diode load circuit to substantially the same value as the direct current impedance of this load circuit. It is not desirable to overcompensate so as to make the alternating current impedance greater than the direct current impedance because when this is the case the effective input resistance offered by the diode and its associated circuit to the input wave applied to tuned circuit 2 is greater with respect to the sideband than with respect to the carrier. The result of this is that when a signal having a depth of modulation approaching 100% is applied, for example, by inductive coupling to the tuned circuit 2, the resulting carrier frequency current flow in tuned circuit 2 contains a larger percentage of sideband and a smaller percentage of carrier than the original modulated wave, and thus is likely to correspond to an over-modulated condition in circuit 2.

In the above discussion it has been assumed for the sake of simplicity, that the impedances M, N, P, Q, were all purely resistive and that the desired negative admittance which is to be presented at the terminals x—x was a pure negative conductance. In practice, for a very accurate compensation of the excess admittances occurring for alternating current, it may be desirable to produce a negative admittance of some other type than the pure negative conductance. For instance, it may be desired to neutralize not only the purely resistive conductance of resistor 4, but likewise the shunted capacitive admittance of the wiring, and also perhaps of the amplifier circuit itself.

I have found that the negative admittance unit shown to the right of the terminals $x-x$ in Fig. 1, may be used not only to produce the effect of a negative conductance, but generally to produce the effect of negative admittance of any type. For this purpose it is merely necessary to replace the resistor P by an impedance of desired character such as an inductance, a capacity, or a complex impedance. Thus if the resistor P be shunted by a small capacity the resulting negative impedance produced at the terminals $x-x$ will neutralize not only resistor 4 , but also stray capacities which may exist across this resistor.

Fig. 2 represents an alternative arrangement which may in some cases be preferred, especially when it is desired to improve the direct current to alternating current impedance ratio of a diode detector which is already connected to an existing audio amplifier with a minimum of alterations to the existing amplifier. In the circuit of Fig. 2, the parts corresponding to parts already described in Fig. 1, are designated by the same reference characters distinguished by the addition of primes. The apparatus to the left of the terminals $x'-x'$ is illustrated, for the sake of generality, as comprising a diode of the so-called full wave or duplex type rather than a simple half wave diode, but actually such apparatus may correspond exactly to the apparatus to the left of the terminals $x-x$ in Fig. 1. The negative impedance and amplifier unit to the right of the terminals $x'-x'$ is, however, based upon a different principle from the negative impedance unit shown in Fig. 1. The unit shown in Fig. 2 has a positive feedback resistor P' connected from the ungrounded side of the output $o'-o'$ to the ungrounded side of the input $x'-x'$. The connection of such a feedback resistance P' tends to produce a regeneration unless Q' has zero impedance, and in order to overcome such an effect a negative feedback or degeneration is provided by means of the voltage divider M', N' which serves to make the cathode of tube $t1'$ more positive at those instants when the plate of tube $t2'$ becomes more positive, thus causing degeneration. It should be noted that in the negative impedance unit of Fig. 2 the cathode of tube $t2'$ is by-passed to ground by condenser $8'$ and biased by cathode resistor $7'$ somewhat like the cathode of tube $t1$ in Fig. 1. The cathode of tube $t1'$ on the other hand, has a potential different from ground as determined by the drop across resistance N' . In each case the suppressor grid is tied to the cathode and the screen grid is by-passed to the cathode.

The negative admittance across terminals $x'-x'$ of the negative admittance unit of Fig. 2 is

$$M' - \frac{M' + N'}{a}$$

$$\frac{P'N' + \frac{M' + N'}{a}P'}{P'N'}$$

which is roughly

$$\frac{M'}{P'N'}$$

where a is large.

Although the invention is illustrated as applied to a diode rectifier of either the half wave or full wave type, it will be understood that it is equally applicable to other rectifiers such as, for example, dry disc rectifiers of the copper oxide or selenium type. It should also be noted

that the outputs may be taken at different points from those indicated in the figures. In Fig. 1, for example, the output as shown, does not have either side grounded. If desired the output could be taken between the upper terminal o and ground in Fig. 1 although in such case the impedance of the output would have to be taken into consideration since it would be effectively across the terminals $x-x$.

The negative admittance units of the present invention are useful not only in connection with a detection arrangement as shown, but also generally for all other applications where a negative admittance of stable character is desired. The negative admittance unit of Fig. 1 (shown to the right of the terminals $x-x$) may, for example, be connected directly across a tuned L. C. unit such as the circuit 2, for the purpose of neutralizing the resistive admittance of this tuned circuit so as to raise its effective reactance resistance ratio. It is well known that an anti-resonant circuit may be considered equivalent to a pure inductance and pure capacitance and a shunted high resistance. Thus the connection of a negative conductance almost equal to the positive conductance of the equivalent shunt resistor will almost neutralize this equivalent shunt resistor and thus leave a circuit practically equivalent to a pure conductance shunted by a pure capacitance. If the negative conductance is made as large as the positive conductance of the equivalent shunt resistor the system will oscillate. Such a system has many uses which are well known per se.

As previously mentioned, when M, N, P, Q are all purely resistive the negative admittance presented by either of the units of Figs. 1 or 2 will be substantially a pure conductance. If, on the other hand, the impedance P or P' is reactive or complex the effective admittance of the whole unit will be correspondingly reactive or complex so that the impedance of the unit at $x-x$ will be like the impedance at P but with a negative sign. If, for example, P or P' is inductive while the other quantities remain resistive, the negative admittance presented will correspond to the admittance of a negative inductance; that is, it will be similar to a capacitance in its phase characteristic, but will become smaller in magnitude with rising frequency, thus corresponding to an inductance in its frequency characteristic. Although it is preferred to employ P or P' as the generalized impedance for determining the character of the negative admittance of the units the impedance N or N' may be used instead of P or P' as the controlling impedance. The impedance Q and M' also exert control but in inverse fashion.

Although I prefer to use one of the types of negative admittance units shown in Figs. 1 or 2, for equalizing the alternating current and direct current impedances of a diode detector, other known types of negative admittance units may be employed. Furthermore, as above mentioned, it is ordinarily sufficient to employ a negative conductance rather than a more complex negative admittance and, therefore, known types of devices suitable for giving negative conductance may be employed.

Although certain particular embodiments of my invention have been shown and described for the purposes of illustration, it will be understood that various adaptations, alterations and modifications thereof occurring to one skilled in the art may be made without departing from the

scope of my invention as defined in the appended claims.

What I claim is:

1. A device for presenting to an external circuit a current voltage characteristic corresponding to a negative admittance, which comprises an amplifier having an input including a grid lead and a cathode lead and an output, a first impedance joined in series with said external circuit to form a first voltage divider, a connection from the junction between said external circuit and said impedance to the grid lead, a second and a third impedance joined in series with each other to form a second voltage divider, a connection from the junction between said second and third impedances to the cathode lead, and means connecting said two voltage dividers in parallel across said output.

2. A device for presenting to an external circuit a current voltage characteristic corresponding to a negative admittance, which comprises a two-stage resistance coupled amplifier having an input and an output, three impedances connected to each other and to said external circuit to form a bridge, connections including a blocking condenser extending from said output to one diagonal of said bridge, and direct connections from the other diagonal of said bridge to said input.

3. A device for presenting to an external circuit a current voltage characteristic correspond-

ing to a negative admittance, which comprises a first and a second space discharge tube each having a cathode and a grid and an anode, means for applying operating potentials to said electrodes, three impedances connected to each other and to said external circuit to form a bridge having first and second corners diagonally opposite one another and third and fourth corners also diagonally opposite one another, a connection including a blocking condenser extending from the anode of said second tube to the first corner of said bridge, a direct connection from the cathode of said second tube to the second corner of said bridge, two further direct connections from the third and fourth corners of said bridge to the grid and cathode of said first tube, respectively, and a connection including a second blocking condenser extending from the anode of said first tube to the grid of said second tube whereby the anode and cathode of said first tube are coupled to the grid and cathode of said second tube over said second blocking condenser and one of said impedances.

4. A device according to claim 3, wherein said first and fourth corners of said bridge are adjacent said external circuit.

5. A device according to claim 3, wherein said second and third corners of said bridge are adjacent said external circuit.

FREDERICK E. TERMAN.
